(57) CLAIM

The ornamental design for a vase for flowers having a heart-like shape, as shown and described.

DESCRIPTION

FIG. 1 is a top, front and right side perspective view of a vase for flowers having a heart-like shape according to my new design;

FIG. 2 is a top, front and right side perspective view thereof, shown with the center element separated, for ease of disclosure; and,

FIG. 3 is a top, rear and right side perspective view thereof, shown in a storage state.

1 Claim, 3 Drawing Sheets

FIG. 1

FIG. 3
